(57) **CLAIM**

The ornamental design for a mounting frame for light source module, as shown and described.

DESCRIPTION

FIG. 1 is a front, top and left side perspective view of a mounting frame for light source module, showing an initial embodiment of our new design;

FIG. 2 is a front, top and right side perspective view thereof;

FIG. 3 is a front view thereof;

FIG. 4 is a back view thereof;

FIG. 5 is a top view thereof;

FIG. 6 is a bottom view thereof;

FIG. 7 is a left side view thereof;

FIG. 8 is a right side view thereof;

FIG. 9 is a sectional view of FIG. 3, taken along line 9-9 of Fig.3 thereof;

FIG. 10 is a reference enlarged perspective view of FIG. 1 thereof;

FIG. 11 is a reference enlarged perspective view of FIG. 2 thereof;

FIG. 12 is a partially enlarged front view of FIG. 3 thereof;

FIG. 13 is a partially enlarged back view of FIG. 4 thereof;

FIG. 14 is a partially enlarged sectional view of FIG. 3, taken along line 14-14 of FIG. 3 thereof;

FIG. 15 is a reference enlarged front perspective view showing state in discrete thereof;

FIG. 16 is a reference enlarged back perspective view showing state in discrete thereof; and,

FIG. 17 is a reference view showing state in use thereof.

The dot dash dot lines immediately adjacent to the shaded areas represent bounds of the claimed design. The broken lines of the mounting frame for light source module are directed to environment which form no part of the claimed design.
